GRID BIAS ARRANGEMENTS IN THERMIONIC VALVE CIRCUITS

Léon Ladislas de Kramolin, Berlin-Pankow,
GermanyApplication July 19, 1929, Serial No. 379,468
In Germany July 27, 1928

7 Claims. (Cl. 250—27)

This invention relates to multi-tube amplifiers, some or all of the tubes of which have equipotential cathodes.

One object of the invention is the provision of improved means in such apparatus for obtaining the desired grid bias without giving rise to back-coupling between the various stages of the amplifier.

Other objects and advantages will appear hereinafter.

It is the general practice, in mains driven radio receiving sets, to take the necessary grid bias potential for each of the tubes of a multi-tube amplifier from a common resistance situated in the lead from the negative terminal of the source of high tension. Experiments have shown, however, that this common resistance acts, particularly in the case of amplifiers of which all the stages work at the same frequency, such as multi-stage high frequency or multi-stage low frequency amplifiers, as a coupling between the various grid circuits. As is well-known it has been attempted to overcome this difficulty by the use of large condensers (of several micro-farads capacity) in parallel with the resistance. Apart from their high cost, however, condensers of this type are undesirable.

The present invention provides a means of avoiding this coupling effect in a multi-tube amplifier, without necessitating the use of condensers for this purpose, so as to provide an amplifier that is free not only from alternating current hum but also from back-coupling.

The invention consists essentially in the substitution for the single common resistance usually employed, of a separate resistance for each tube of the amplifier.

The heating current is preferably taken from a common heating winding for all of the tubes and the individual resistance for each tube connected between the respective cathode and a point connected both to the mid-point of the heating winding and the high tension negative terminal.

Two embodiments of the invention are shown in the accompanying drawing in which:

Figure 1 shows the invention applied to three indirectly heated cathode tubes supplied from the mains,

Figure 2 shows the invention applied to an indirectly and a directly heated cathode tube used in combination.

Referring to Figure 1: The three tubes 1 have their filaments 3 supplied from the mains through a transformer 4. The rectangles 5 in the grid

and anode circuits represent any desired inter-valve coupling. A lead 6 from the negative terminal of the source of high tension is connected to the centre point of the secondary winding of the transformer 4 and to the three parallel resistances 7 the other ends of which are connected to the cathodes 8 of the respective tubes. Owing to the difference of potential between the filaments 3 and the cathodes 8, there is a fall of potential along each of the resistances 7, which thus serve as potentiometers from which the necessary biasing potential for the grids 9 may be taken.

In the construction shown in Figure 2, the grid biasing potential for the directly heated cathode valve 2 is taken from a resistance 11 included in the lead 6 from the negative terminal of the source of high tension. The grid biasing potential for the indirectly heated cathode tube 1 is obtained from the resistance 7 as described with reference to Figure 1.

What I claim and desire to secure by Letters Patent is:—

1. In a mains-energized radio receiving apparatus employing at least one indirectly heated tube and one directly heated tube, the combination of a common heating winding for said tubes, an individual resistance for each tube

connected in the negative part of the cathode-plate circuit of the respective tube, and means connecting the grids of said tubes to the respective resistances for obtaining the necessary grid bias.

2. In a mains-energized apparatus employing an indirectly heated thermionic tube and a directly heated thermionic tube, the combination of a heating winding common to both indirectly and directly heated tubes, an individual resistance for each tube connected in the negative part of the respective cathode-plate circuit and electrically connected to the mid-point of said heating winding and means connecting the grids to the respective resistances for obtaining the necessary grid bias.

3. In a mains-energized apparatus employing an indirectly heated thermionic tube and a directly heated thermionic tube, the combination of a heating winding common to both indirectly and directly heated tubes, an individual resistance for the indirectly heated tube connected between the cathode and a point connected to both said heating winding and the high tension negative, an individual resistance for the directly heated tube connected between said heating winding and high tension negative, and

- means connecting the grids to the respective resistances for obtaining the necessary grid bias.
4. In a multi-stage amplifier, a plurality of thermionic tubes connected in cascade for amplifying the same incoming signal frequency, at least one of said tubes being provided with an equi-potential cathode, a common heating circuit for the cathodes of said tubes, a source of plate current common to said tubes, inter-stage coupling devices connected in the plate leads from said source, means for biasing the grids of said tubes comprising resistances each of which is entirely individual to a single tube and is connected between the cathode of its corresponding tube and the negative terminal of the plate current source, and means connecting the grids of the tubes to the respective resistances for obtaining the desired grid bias.
5. In a mains energized multi-tube amplifier, a plurality of thermionic tubes having equipotential cathodes, said tubes being connected in cascade for operation at approximately the same signal frequency, a mains transformer having a heater winding common to all the heaters of said cathodes, a source of plate current common to said tubes, inter-stage coupling devices connected in the plate leads from said source, a resistance individual to each tube and connected between the cathode of its corresponding tube and the negative terminal of the plate current source, and means connecting the grids of the tubes to the respective resistances for obtaining the desired grid bias, said resistances comprising the sole means for obtaining the desired bias on the grids of the tubes.
6. In a mains energized multi-tube amplifier, a plurality of thermionic tubes having equipotential cathodes, all of the tubes being connected in cascade for operation at approximately the same signal frequency, a source of plate current common to said tubes, inter-stage coupling devices connected in the plate leads from said source, a mains transformer having a heater winding common to all the heaters of said cathodes, a resistance individual to each tube and connected between the cathode of its corresponding tube and a point connected to both the mid-point of said heater winding and the negative terminal of said plate current source, and means for connecting the grids of the tubes to the respective resistances for obtaining the desired grid bias, said resistances comprising the sole means for obtaining the desired bias on the grids of the tubes.
7. In a mains energized multi-tube amplifier, a plurality of thermionic tubes having equipotential cathodes, said tubes being connected in cascade for operation at approximately the same signal frequency, a source of heater current common to all the heaters of said cathodes, a source of plate current common to said tubes, inter-stage coupling devices connected in the plate leads from said source, a resistance individual to each tube and connected between the cathode of its corresponding tube and the negative terminal of said source of plate current, and means for connecting the grids of the tubes to the respective resistances for obtaining the desired grid bias, said resistances comprising the sole means for obtaining the desired bias on the grids of the tubes.
